DETERGENT COMPOSITIONS

Pieter L. Kooijman, Cornelis Kortland, and Petrus W. Slokker, Amsterdam, Netherlands, assignors to Shell Oil Company, New York, N.Y., a corporation of Delaware

No Drawing. Filed Sept. 10, 1956, Ser. No. 608,707
Claims priority, application Netherlands Sept. 16, 1955
8 Claims. (Cl. 252—161)

This invention relates to new compositions having detergent properties. More particularly, it pertains to compositions containing synthetic sulfated and sulfonated organic detergents of certain specific types in controlled proportions which have an exceptionally valuable combination of properties.

It has previously been proposed to produce detergent compositions containing synthetic sulfated and sulfonated organic detergents of certain kinds for special purposes. Thus U.S. Patent 2,631,980 claims mixtures of C_{12} — C_{15} alkylbenzene sulfonates with C_8 — C_{12} alkyl sulfates containing 10 to 30% of the latter to prevent caking of the solid detergent. However, all such previous compositions have certain disadvantages in one or more respects and it is an object of the present invention to provide new detergent mixtures having improved properties compared with such prior products.

A special object of the invention is the provision of mixtures of alkyl aryl sulfonate detergents and alkyl sulfate salt detergents which not only have an especially advantageous combination of desirable surface-active properties but also form concentrated solutions in water which are stable to precipitation and gelling at low temperatures and so are eminently adapted for use as liquid detergent compositions. Because of the special advantages of the new detergent mixtures in solutions suitable for sale in the rapidly increasing market for liquid household detergents, for instance, this form of the new compositions will be emphasized in the following description of the invention, but it will be understood that the new detergent mixtures are not restricted to such use and can be advantageously employed as solid products in powder, flake, bar or other conventional forms.

It has been found that mixtures of alkyl aryl sulfonate detergents and alkyl sulfate salt detergents which satisfy a number of very specific requirements have outstanding surface-active properties combined with a cold stability superior to other mixtures of these detergents. Thus the particular alkyl aryl sulfonate and alkyl sulfate salt detergents of the new compositions when used in the proportions of the invention show synergistic effects especially as regards the cold stability of their solutions. This cold stability is conveniently measured by clear point determinations, the clear point being the temperature, expressed in degrees centigrade, at which a turbid aqueous solution of the detergent mixture of given concentration clarifies during gradual heating.

The detergent mixtures of the invention having these advantageous properties are mixtures of alkyl aryl sulfonates having 8 and/or 9 carbon atoms in the alkyl groups, preferably together with one or more alkyl aryl sulfonates with 10, 11, 12 or 13 carbon atoms in the alkyl groups and substantially free from alkyl aryl sulfonates comprising less than 8 or more than 13 carbon atoms in the alkyl groups in admixture with mixtures substan-

2

tially consisting of alkyl sulfates with 8 or 9 to 18 carbon atoms in the molecule in weight ratios between 60:40 and 20:80.

Surprisingly it has been found that the clear point, 5 and foaming and wetting properties of these alkyl aryl sulfonate-alkyl sulfate salt detergent mixtures can be improved still further by adding thereto a condensation product of an alkylphenol and ethylene oxide or, in other words, an alkylphenol monoether of polyethylene glycol having 7, 8 or 9 carbon atoms in the alkyl group and 8 to 10 ethylene oxide groups per molecule or a mixture of such alkylphenol ethers. These new and especially advantageous ternary mixtures are an especially important feature of the invention.

10 As previously indicated it is essential in order to obtain products with the advantageous properties of the new compositions of the invention, particularly the great reduction in cold point which is desired, that the mixture contain an alkyl aryl sulfonate having either 8 or 9 carbon atoms in the group or of a mixture of such alkyl aryl sulfonates as the alkyl aryl sulfonate detergent component of the new detergent mixture or be present in substantial amount in such component. Alkyl aryl sulfonates with longer alkyl groups have been found to promote 15 the detergent effect of the mixture and can therefore be added thereto chiefly for this purpose, but alkyl aryl sulfonates with alkyl groups having more than 13 carbon atoms were found to have an unfavorable effect. 20 On the clear point of the mixture, and therefore the mixtures of the invention should be essentially free from such compounds.

Thus, for example, alkyl aryl sulfonate mixtures with alkyl groups comprising 10 and 11, or 10, 11 and 12, or 10, 11, 12 and 13, or 11, 12 and 13, etc., carbon atoms 25 are suitable for use in the present mixtures in addition to the essential C_8 - and/or C_9 -alkyl aryl sulfonates. But mixtures of alkyl aryl sulfonates in which the number of carbon atoms in the alkyl groups do not form successive series, and thus, for example, comprise 10 and 12, 10 and 30 13, 10, 11 and 13 or 11 and 13 carbon atoms, may likewise be used with the C_8 - and/or C_9 -alkyl aryl sulfonates with good results.

Alkyl aryl sulfonates which are particularly suitable for use in the process according to the invention may be 35 prepared by alkylation of benzene or naphthalene, or substitution products thereof such as toluene, methyl naphthalene, etc., using HF or H_2SO_4 as alkylation catalyst, with an olefin mixture obtained by the vapor-phase cracking of paraffin waxes or by cracking by solvent extraction 40 refined catalytically cracked heavy oil, or by polymerization of alkenes such as propene as used for the preparation of propylene tetramers. The olefins used, of course, are those having the number of carbon atoms required to give the above indicated alkyl groups. The alkylate is sulfonated and neutralized in the customary way. The alkyl sulfates chosen are preferably water-soluble secondary alkyl sulfate salt detergents prepared via sulfation of a mixture substantially consisting of C_8 45 or C_9 to C_{18} olefins obtained in one of the two ways just described.

In very many cases the mixtures of compounds to be used for the alkylation and the preparation of alkyl sulfates will be obtained by distilling mixtures which, in 50 addition, contain compounds with more and/or fewer

on atoms than the required lower or upper limit, so the mixture of initial material to be used finally usually always contains a small percentage, say approximately, for example, not more than 5% of compounds with more or fewer carbon atoms than the upper or lower limits indicated.

Thus, for example, a C_8 or C_9 to C_{18} olefin mixture prepared in the above manner will virtually always contain a small percentage of C_7 , and sometimes a number of far fewer, C_6 olefins, and also a small percentage of C_{19} and traces of C_{20} olefins. As is usual in practice, a mixture of this type is also referred to here as a C_8 or C_9 to C_{18} olefin mixture and the sulfate prepared therefrom as a C_8 or C_9 to C_{18} alkyl sulfate. The same applies to the designation of the alkyl aryl sulfonates, so that, for example, an alkyl aryl sulfonate mixture referred to as the term C_8 or C_9 to C_{13} may also contain a small percentage of C_7 and C_{14} alkyl aryl sulfonates.

The preferred alkyl aryl sulfonates are the water-soluble monoalkylbenzene monosulfonic acid salts, particularly the alkali metal, for instance potassium, or ammonium or amine salts. Similar salts are preferred in the C_8 or C_9 to C_{18} alkyl sulfate salt detergent component of the new mixtures. These alkyl sulfate salts are advantageously mixtures predominating in light or substantially straight chain 2-alkylsulfate salts.

Greatest improvements in foaming, wetting properties and clear point have been obtained by use of ternary detergent mixtures of the previously described polyethylene glycol with alkylphenol monoethers with C_8 - C_{13} benzene monosodium sulfonates and C_8 - C_{18} secondary alkyl sodium sulfates.

The amount of alkylphenol-polyethylene glycol monoether which should be present with the indicated alkyl sulfonate and alkyl sulfate salt detergent mixtures will depend upon the properties desired in the final product.

Even relatively small amounts of the specified phenolpolyethylene glycol monoethers in the new compositions give marked improvements in the wetting and foaming properties as well as in the clear point of alkylbenzene sulfonate-secondary alkyl sulfate salt detergent mixtures. For instance, a mixture in which detergents are in the proportions, by weight, of approximately 36% C_8 - C_{13} alkylbenzene sodium sulfonates, 5% secondary alkyl sodium sulfates, and 10% phenol polyethylene glycol monoether containing 5 ethylene glycol units, has wetting and foaming values of 140 and 150, respectively, compared with the C_{18} secondary alkyl sodium sulfates taken as 100, the clear point of a 21% w. aqueous solution of the mixture is well below 0° C. The foaming properties of the mixture exceed that of each of its three detergent components. With increasing amounts of the alkylphenol-polyethylene glycol ethers the wetting and foaming properties of the mixture increase. For example, a mixture in which the proportions of the three detergent components are 30% C_8 - C_{13} alkylbenzene sodium sulfonates, 50% C_8 - C_{18} secondary alkyl sodium sulfate and 20% octylphenol polyethylene glycol monoether with 5 ethylene glycol units, the relative wetting and foaming values, on the same basis, are 200 and 160, respectively, and the clear point is below 0° C. even in solution of 34% concentration. While higher proportions may be used as a general rule it is preferred to employ from 2% to about 30%, more preferably about 10% to about 20% of the specified alkylphenol polyethylene glycol monoethers based upon the total weight of the detergents used.

These new compositions can be prepared by blending together the preformed alkyl aryl sulfonate and alkyl sulfate salt detergents having the required structures, or without the specified alkylphenol polyethylene glycol monoethers, in the indicated proportions. Advantageously the alkyl aryl sulfonate and alkyl sulfate salt

detergents can be produced together by the method of the application of two of us (Kortland and Kooijman) with Ferdinand A. Doorman, filed simultaneously herewith. In this method the alkyl sulfate salts are preferably formed by adding the corresponding olefins to the alkyl aryl hydrocarbon sulfonation product and carrying out sulfation of the olefins with excess sulfonating agent present therein. For highest yields the sulfonation is carried out with oleum of, for example, 20% free SO_3 concentration using a mole ratio of SO_3 to alkyl aryl hydrocarbon of about 5 to 7:1. In a variation of this process the alkyl aryl sulfonic acids and alkyl sulfuric acids can be separately prepared and mixed together in the required ratio, after which the mixture is neutralized and extracted preferably with a liquid hydrocarbon such as gasoline to remove unconverted organic material and/or other undesirable impurities.

The alkyl aryl sulfonate and alkyl sulfate salt detergents employed in the new compositions will usually contain a certain amount of inorganic salt, particularly the sulfate corresponding to the base used in the neutralization step in their preparation. It may be desirable to add other builders such as phosphates, silicates, carbonates, foam stabilizers, washing promoters, bleaching agents, and the like, depending upon the intended use of the products. The new compositions can also be used in admixture with other detergents. When the compositions are to be used in solution, for instance sold as liquid detergents, it is desirable that the inorganic salt content be below about 25% and more advantageously not greater than about 15%. The active ingredient content, i.e. the total weight of alkyl aryl sulfonate detergent, alkyl sulfate salt detergent and alkylphenol polyethylene glycol monoethers, in such cases is preferably between about 10% and about 50%, more preferably about 20% to about 40% by weight of the solution.

The invention is further illustrated by the following non-limiting examples.

EXAMPLE I

A mixture of alkylbenzene sulfonates, prepared in any of the usual ways, the alkyl groups of which contained 9 to 12 carbon atoms, was mixed in a stirred mixing vessel with C_8 to C_{18} alkyl sulfates in such a ratio that the resulting mixture contained 40 parts by weight of alkylbenzene sulfonates and 60 parts by weight of alkyl sulfates. The clear point of this mixture, which was diluted with water to a 7% concentration, was found to be situated at 1° C. A 40% solution still had a clear point of only 9° C.

EXAMPLE II

Benzene was alkylated in a stirred reactor with a C_8 to C_{13} olefin mixture obtained by vapor phase cracking of a catalytically cracked refined heavy hydrocarbon oil.

The alkylation was started with a mixing ratio of benzene to olefins of 10:1. Hydrogen fluoride was used as catalyst, care being taken to ensure a phase ratio of the total quantity of hydrocarbons to hydrogen fluoride of 1:1 by volume. The residence time in the reactor was 30 minutes at room temperature, stirring being carried out at a rate of 220 r.p.m. The pressure was 4 atmospheres absolute.

After the alkylation reaction was complete the excess of benzene was distilled off at atmospheric pressure. By separating a small quantity of light and heavy ends from the remaining alkylate mixture at 40 mm. Hg, an alkylate was obtained which had a sulfonatability not exceeding 90%.

The alkylate thus prepared was sulfonated at 55° C. with oleum containing 23% by weight of free SO_3 , starting from a mole ratio of SO_3 to alkylate of 6.3:1. Towards the end of the sulfonation reaction there was added to this mixture a quantity of C_8 to C_{18} olefins which was thus sulfated. The quantity of olefins added

was so selected that the resulting mixture contained 40 parts by weight of alkylbenzene sulfonic acids and 60 parts by weight of C_9 to C_{18} alkyl sulfonic acid.

The mixture thus obtained was neutralized with a caustic soda solution and saponified in order to convert the dialkyl sulfates present into monoalkyl sulfates. After adding 25% by weight of isopropyl alcohol liquid phase desalting was then carried out. An extraction was then carried out with gasoline as a result of which unconverted organic material was removed. Finally, the solution was boiled down until the desired concentration was obtained.

The concentrate prepared in this way was split into three portions which were diluted with water to 20%, 34%, and 40% concentrations, respectively. The clear points thereof were found to be 2° C., 7° C. and 8° C., respectively.

By applying the variant just described to the process according to the invention it was possible to obtain an improvement in the yield of 15%, calculated on olefins, as compared to the preparation of the same mixture by mixing in the usual way portions of C_9 to C_{18} alkyl aryl sulfonates and C_9 to C_{18} alkyl sulfates prepared separately.

EXAMPLE III

In the following tables the foaming and wetting figures as well as the clear points are given by two mixtures, one comprising a mixture of C_8 to C_{18} secondary alkyl sodium sulfonates and C_8 to C_{18} alkylbenzene sodium sulfonates in a weight ratio of 60:40, mixed with octylphenol polyethylene glycol monoether containing 9-9.5 ethylene glycol units in quantities varying from 0-30% w., while the other comprises a mixture of C_8 to C_{18} secondary alkyl sodium sulfonates and C_8 to C_{18} alkylbenzene sodium sulfonates in a weight ratio of 45:55 also in admixture with octylphenol polyethylene glycol monoether containing 9-9.5 ethylene glycol units in quantities varying from 0-30% w.

The figures given in the tables for the foam and wetting performance are based on those of C_8 to C_{18} secondary alkyl sodium sulfonates which have been taken to be 100.

When comparing the figures for these compositions having different weight ratios of C_8 to C_{18} secondary alkyl sodium sulfonates to C_8 to C_{18} alkylbenzene sodium sulfonates with each other it can be concluded that the foaming being substantially equal for the preparations comprising a similar percentage of the octylphenol polyethylene glycol ether, the wetting performance and the clear point where the weight ratio is 45:55 are still better than where the ratio is 60:40.

Table I

C_8 to C_{18} Alkyl Sulfate Salts and Alkylbenzene Sulfonates, Total Wt. percent	Octylphenol Polyethylene Glycol Ether, Wt. percent	Foaming	Wetting	Clear Points, ° C.	
				21% Active Material	34% Active Material
Wt. Ratio 60:40:					
100	0	107	133	3	7
95	5	125	143	3	7
90	10	140	150	2	6
80	20	153	165	0	5
70	30	158	190	<0	2
Wt. Ratio 45:55:					
100	0	108	152	<0	10
95	5	125	160	<0	4
90	10	140	168	<0	0
80	20	158	187	<0	0
70	30	163	200	<0	<0

EXAMPLE IV

Other compositions in accordance with the invention which have the previously indicated desirable combination

of properties are the following in which the proportion by weight:

		Percent
A		
6	C_8 - C_{18} alkylbenzene sodium sulfonate	19
10	C_8 - C_{18} 2-normal-alkyl sodium sulfate	76
	Sodium sulfate	5
10	Octylphenol polyethylene glycol ether with 8.5-9 ethylene glycol units (avg.)	None
B		
15	C_8 - C_{18} alkyltoluene potassium sulfonate	40.5
	C_8 - C_{18} secondary alkyl potassium sulfate	49.5
	Potassium sulfate	10
15	Heptylphenol polyethylene glycol ether with 8 ethylene glycol units	None
C		
20	C_8 - C_{18} alkylbenzene ammonium sulfonate	43
	C_8 - C_{18} secondary alkyl sodium sulfate	29
	Ammonium sulfate	2
20	Sodium sulfate	2
	C_8 - C_{18} secondary alkylphenol polyethylene glycol with 9.5 ethylene glycol units (avg.)	None
D		
25	Octylnaphthalene monosodium sulfonate	30
	C_8 - C_{18} secondary alkyl sodium sulfate	70
	Nonylphenol polyethylene glycol ether with 10 ethylene glycol units	None
E		
30	C_8 - C_{18} alkyltoluene sodium sulfonate	21.5
	C_8 - C_{18} secondary alkyl sodium sulfate	64.5
	Sodium sulfate	4
	Sodium pyrophosphate	10
30	C_8 - C_{18} alkylphenol polyethylene glycol ether with 9 ethylene glycol units (avg.)	None

We claim as our invention:

1. A detergent composition forming cold stable aqueous solutions of about 10% to about 50% detergent content, consisting essentially of an alkyl aryl hydrocarbon monosulfonic acid water-soluble salt having an alkyl group of 8 to 9 carbon atoms but essentially free of alkyl aryl sulfonate salts containing alkyl groups of less than 8 and more than 13 carbon atoms, together with a secondary alkyl sulfate salt consisting essentially of a secondary alkyl sulfate water-soluble salt having at least 8 to 9 but not more than 18 carbon atoms per molecule, said sulfonate and alkyl sulfate salt being present in a weight ratio of from 60:40 to 20:80, and an alkyl phenol polyethylene glycol monoether having 7 to 9 carbon atoms in the alkyl group and 8 to 10 ethylene glycol units in the molecule, the amount of said ether being between about 2% and about 30% of the total weight of the detergent composition.
2. A detergent composition in accordance with claim 1 wherein the alkyl aryl sulfonate present in the mixture includes a substantial amount of an alkyl aryl sulfonate having at least 10 but not more than 13 carbon atoms in the alkyl groups.
3. A detergent composition in accordance with claim 1, wherein the alkyl aryl sulfonate is an alkyl monocyclic aromatic hydrocarbon monosulfonic acid water soluble salt.
4. A detergent composition in accordance with claim 1, wherein the alkyl aryl sulfonate salt is alkyl benzene sodium sulfonate and the alkyl phenol polyethylene glycol monoether content is between about 10% and about 30% of the total weight of said detergent composition.
5. A detergent composition forming cold stable aqueous solutions of about 10% to about 50% detergent content, consisting essentially of a monoalkylbenzene monosulfonic acid sodium salt wherein the alkyl group contains 8 to 9 through 13 carbon atoms and a secondary alkyl sulfate sodium salt of 8 to 9 through 18 carbon atoms per molecule which is a predominantly straight chain 2-alkyl sulfate salt, and an alkylphenol polyethylene glycol monoether having 7 to 9 carbon atoms in the alkyl group and 8 to 10 ethylene glycol units, the weight ratio of sulfonate

to alkyl sulfate salt being from 60:40 to 20:80 and content of said alkyl phenol ether being about 10% to 30% of said detergent composition.

A detergent composition in accordance with claim 5, wherein each alkyl group of the alkylbenzene sulfonate alkyl sulfate salt is derived from olefinic products of r phase cracking of paraffinic hydrocarbons.

A liquid detergent composition consisting essentially water, less than about 25% of inorganic salts, and mixture of an alkyl aryl hydrocarbon monosulfonic water-soluble salt having an alkyl group of 8 to 9 carbon atoms but essentially free of alkyl aryl sulfonate containing alkyl groups of less than 8 and more than 15 carbon atoms and a secondary alkyl sulfate salt consisting essentially of a secondary alkyl sulfate water-soluble salt having at least 8 to 9 but not more than 15 carbon atoms per molecule, said sulfonate and alkyl sulfate salt being present in a weight ratio of from 10 to 20:80, and an alkyl phenol polyethylene glycol ether having 7 to 9 carbon atoms in the alkyl group and 8 to 10 ethylene glycol units in the molecule, amount of said ether being between about 2% and 30% of the total weight of the mixture, said mixture being between about 10% to about 50% by weight of the liquid detergent composition.

A liquid detergent composition consisting essentially of water and a ternary mixture consisting of a monoalkylbenzene monosulfonic acid salt wherein the alkyl group

contains 8 to 9 through 13 carbon atoms, a secondary alkyl sulfate sodium salt of 8 to 9 through 18 carbon atoms per molecule which is a predominantly straight-chain 2-alkyl sulfate salt, and an alkyl phenol polyethylene glycol monoether having 7 to 9 carbon atoms in the alkyl group and 8 to 10 ethylene glycol units, the weight ratio of sulfonate salt to alkyl sulfate salt being from 60:40 to 20:80, and the content of said alkyl phenol ether being about 10% to about 30% of said ternary mixture, said ternary mixture being between about 20% and about 40% by weight of the liquid detergent composition.
